ENGINE STARTER

Raymond P. Lansing, Montclair, N. J., assignor,
by mesne assignments, to Eclipse Aviation Corporation,
East Orange, N. J., a corporation of
New Jersey

Application April 25, 1932, Serial No. 607,459

6 Claims. (Cl. 123—179)

This invention relates to engine starters and more particularly to a starter of the inertia type.

An object of the present invention is to provide novel transmission means in a starter of the foregoing type whereby energy may be stored in the inertia member of the starter and thereafter utilized to start the engine.

A further object is to provide an engine starter of the foregoing type embodied in a novel construction possessing practical merit and insuring efficiency, flexibility and reliability in operation. In this connection, a feature of the invention which provides extreme flexibility and adaptability to varying conditions, is the provision of means whereby it is possible to accelerate the inertia member of the starter by actuation of a cranking shaft, the angular position of which is capable of broad variation with respect to the axis of the member of the gear train with which it engages.

Another object of the invention is to provide in connection with the angle varying and transmission features above referred to, a novel gear construction making it possible to accelerate the inertia member by rotation of the cranking shaft in either a clockwise or counter-clockwise direction without producing corresponding reversal in the direction of rotation of the inertia or engine engaging members.

These and other objects will become apparent upon inspection of the following specification and the accompanying drawings, wherein is illustrated the preferred embodiment of the invention. It is to be expressly understood, however, that the drawings are intended to serve merely as an illustration of one mode of embodying the invention in a practical form, and are not designed as a definition of the limits of the invention, reference being had for this purpose to the appended claims.

In the drawings,

Fig. 1 is a longitudinal sectional view of the device embodying the invention;

Fig. 2 is a transverse section taken substantially along line 2—2 of Fig. 1;

Fig. 3 is a fragmentary view of certain of the parts appearing in a transverse section taken along the line 3—3 of Fig. 1; and

Fig. 4 is a transverse section with certain parts broken away for clearness of disclosure, taken along the line 4—4 of Fig. 1.

Referring more particularly to Fig. 1, the starting mechanism therein shown comprises a flywheel 4 adapted to rotate an engine engaging member 5 having clutch jaws 6 movable into

driving engagement with a complementary clutch member 7 provided on an engine crank-shaft (not shown) or an extension thereof. The starting apparatus is contained in a housing constituted by an inner section 8, an intermediate section 9 and a flywheel cover section 10, the sections being removably secured together in any suitable manner, and the inner section 8 being provided with a flange 11 to facilitate mounting of the starter on the crankcase, a portion of 10 which is diagrammatically shown at 12. The flywheel is adapted to be rotated at high speed in order that sufficient energy may be stored therein for cranking the engine, and a gear train is preferably provided for transmitting the energy stored in the flywheel to the engine engaging member 5; the gear train being so constituted that the member 5 will be rotated at a much lower speed than that of the flywheel. For this purpose a pinion rod 16 is firmly held in the central bore 17 of the hub portion 18 of the flywheel and meshes with a combined gear and clutch member constituted by a toothed ring or gear 20 surrounding a set of friction discs 19 and 21, the former of which are connected to a cylindrical extension 23 of an internally splined collar or gear 24; the latter discs 21 being held by means to be described, for rotation in unison with the ring 20.

These clutch discs are normally held in position to transmit a predetermined torque between the members 20 and 24, such setting being effected by provision of coiled compression springs 26 adjustably held in place by screws 27 threadedly engaging openings 28 provided at angular intervals of equal radial distances from the center of a pressure or abutment plate 29. A similar pressure plate 30, adapted to carry a cover plate 31, is preferably provided at the opposite side of the clutch assembly, the plate 30 being engaged by flanged rim 32 of the spring containing thimbles 33, passing through openings in the discs 21. Thus these thimbles also serve to drivably connect these discs with the plate 29. The plate 30 has also a hub 35 surrounding the splined shaft 36 and spaced therefrom by provision of a pair of bearing sleeves 37, 38. As shown, the shaft 36 is rotatably supported at one end by bearing member 40 received in a pocket 41 of the casing section 8, while the other end is supported by a similar bearing 42 received in a similar pocket 43 in the casing section 9. Suitable means, such as adjustable nut 45 and the shoulder 46 may be provided for locating the shaft 36 in 55

proper position longitudinally of the enclosing casing.

The means for drivably connecting plate 29 with ring 20, as well as for causing the friction clutch members 19 and 21 to yield in the event of an excessive load thereon, comprises a plurality of balls 48 disposed in pockets 49 formed in inwardly extending lugs 50 formed circumferentially about the inner surface of the toothed 10 ring 20, in which pockets the balls 48 are normally held by the pressure of the plate 29, the latter having elongated pockets 52 to receive the balls. On the opposite side of the clutch disc assembly is provided a second group of balls 51 15 associated with the plate 30 and acting to take both the radial thrust loads, as well as constituting a frictionless supporting means for the member 20.

The means for drivably connecting the combined clutch and gear member above described with the engine engaging member 5 preferably includes a toothed portion 55 on the shaft 36 intermediate the collar 24 and the bearing 40, the said toothed portion constituting a pinion adapted to mesh with a spur gear 56 having a short toothed-extension 57 on one side thereof, within which is mounted a bearing 58, in which, with the aid of sleeve 59, the inner end of the pinion shaft 16 is rotatably supported. On the opposite side the gear 56 has a long extension, providing a shoulder portion 60 receiving a bearing member 61, the outer race of which is retained in place in a pocket 62 of the casing section 8. Adjacent the bearing portion 60 of the extension is a finely threaded portion 66 having a nut 67 which adjustably holds in place the inner race of the bearing 61; the portion 66 being followed by a coarsely threaded portion 63 constituting in effect a screw shaft adapted to receive a correspondingly internally threaded sleeve or nut 64 slidably splined at its outer end to the engine engaging member 5 as indicated at 65. With this construction it is apparent that nut 64, due to its inertia, will have a tendency to thread itself along the shaft 45 63 when the latter begins to rotate; but such threading action is delayed until the flywheel has been sufficiently accelerated, the delay being effected by the means next to be described.

As shown best in Fig. 3, the means for delaying relative longitudinal movement between the members 63 and 64, and thus delaying the engagement of the jaws 6 with the engine member 1, preferably takes the form of a vertically disposed rock shaft 80 mounted in a boss 81 extending from one side of the casing section 8 and adapted to receive at its upper end a crank arm 82 for manual or other suitable operation. At its lower end there is secured a similar crank arm 83, on which is positioned a finger 84 engageable 60 with an annular groove 85 formed between the peripheral flanges 86 and 87 on the nut 64. A spring backed plunger 88 is mounted in the boss 81 in such a manner as to normally be urged by spring 89 into engagement with a groove 90 65 milled in the surface of the pin 80 as indicated.

In Fig. 1 a coiled compression spring 70 surrounds a pin 71 serving to couple the engine member 5 with a disc 73 held in place in the nut 64 against a shoulder 74 by suitable means such as 70 split ring 75; the degree of compression of the spring 70 being regulable by adjustment of a nut 76.

The spring backed plunger 88 by virtue of its holding action on pin 80 insures that before the 75 meshing action can be successfully inaugurated,

the force applied to the lever 82 will be sufficient to produce meshing with a snap action, while in the event of any difficulty in the proper meshing of the members 6 and 7, the spring 70, by momentarily yielding, will allow these teeth to align themselves more perfectly.

As an aid to the plunger 88 in maintaining the nut 64 in the non-meshing position during the period of flywheel energization, a coiled torsion spring 68 (Fig. 3) is wound about the pin 80, with one end held to the boss 81 and the end engaging the lever 83 in such a manner as to urge the finger 84 to the left, as viewed in Fig. 1. Thus the spring 68 also acts (through the intermediate nut 64 and the coupling pin 71) to insure a positive return of the member 5 to the demeshed position as soon as the engine starts.

In order to seal the starter against the infiltration of oil from the crankcase or the entry of any other matter which might impair the operation 20 of the starter, there is preferably provided a cup shaped member 91 preferably formed of metal but having at its outer end a flange 92 adapted to be clamped between flange 11 of the starter housing and the mounting flange 12 of the engine crankcase, indicated in broken lines. As shown, this cup member 91 is fitted over the inner end of the casing section 8, at which point it is shouldered to retain in place the flange 93 of a guide sleeve 94 coaxing with the engine member 30 5; the said sleeve 94 also serving to hold in place, with the aid of a second disc 95 a sealing washer 96 of non-metallic material. The members just described also serve to limit the inward movement of the engine member 5 by virtue of their 35 being engaged by the peripheral enlargement 97 provided on the engine member 5.

The novel angularly adjustable and reversible means for energizing the flywheel through the gear train and clutch above described, is herein 40 shown as including a shaft 99 rotatably mounted with the aid of a sleeve 100 in the inwardly extending boss 98 of a cylindrical cage or housing 101, the said cage being adjustable by rotation along the two arcuate surfaces provided in the 45 laterally extending portions 102 and 103 of the casing sections 8 and 9, respectively. By this means the shaft 99 may be set at different times or under different conditions in various positions angularly of the plane on which the section of 50 Fig. 1 is taken, thus making it possible to adapt the starter to varying installation conditions. As indicated in Fig. 2, the shaft 99 may be set relatively to the casing sections 8 and 9 in any one of a large number of different angular positions over a range of approximately one hundred and eighty degrees, by drilling a line of holes 120, a few degrees apart about a portion of the cylindrical walls of the laterally extending faces 102 and 103, and drilling a line of holes 121, of a 60 lesser degree apart, through the wall of the cylindrical cage 101, as indicated at 121; the holes 120 in the casing section 103 being preferably counterbored as indicated at 122 in Fig. 1 for the reception of the heads of screws 123 (Fig. 2) which may 65 be made to pass through aligned holes of the members 102, 103 and 101 to lock the cage and hence the shaft 99 at the desired angle.

Preferably the shaft 99 is counterbored at its outer end for reception of a universal joint 104 70 which in turn coacts with socketed portion 105 serving for attachment of a handcrank or other operating means. At its inner end, the member 99 has adjustably secured thereto, a bevel pinion 75 106 meshing with a corresponding bevel pinion 75

107. As shown, the latter pinion is integral with a shaft 108 supported in the casing 9 by bearing member 110, its other end being received in counterbored portion 112 of a spur gear 114. Also 5 as shown, gear 114 meshes with the pinion 57 and has an elongated hub 115 with a reduced portion 116 rotatably supported by the casing section 8 with the aid of a bearing member 117. Preferably, gear 114 is further provided with an 10 internally toothed annular rim 118; and with the shaft 108 in the position shown in Fig. 1, this rim 118 meshes with the longitudinally extending parallel portions 119 of the bevel teeth of the pinion 107, the member 107 being thus a combination 15 bevel gear and clutch. A second spur pinion 124 is provided near the opposite end of shaft 108 for a purpose to be explained.

In operation, the flywheel is energized from an exterior source of power through the shafts 20 105 and 99, bevel gears 106, 107, the gears and pinions 114, 57, 56, 55, member 24, the friction clutch discs 19 and 21, and the gears 20 and 16. During this period of energization, the shaft 63 and nut 64 rotate as a unit with the gears 56. 25 When, however, the flywheel has been sufficiently energized, the lever 82 is actuated to cause such relative longitudinal movement through the instrumentalities above described, whereupon the member 6 is caused to mesh with the engine member 7 and thus impart initial cranking rotation 30 to the engine.

As soon as the engine has, by the foregoing means, been started in operation under its own power, the resulting excess in speed of the engine 35 member 7 and starter member 6 and nut 64 over that of the screw shaft 63 will cause a reverse longitudinal action on the member 64, thus insuring its return to the position indicated in Fig. 1; the member 5 being at the same time returned 40 through the action of the coupling pin 71, in conjunction with the inclined contour of the abutting jaw teeth.

If in any given installation it is considered 45 more convenient to rotate crankshaft 105 in the reverse direction, but without desiring to change the direction of rotation of the engine member, such a result may be obtained simply by reversing the shaft 108, end for end, thereby bringing the clutch 124 into mesh with the internally toothed 50 rim 118 of the gear 114, the combination spur and bevel pinion 107 now being disposed in abutting relation to the bearing 110, while the end 125 of the shaft is now received in the counter-bored recess 112 of the clutch 114. In this position of 55 the shaft, the pinions 106 and 107 continue to be in mesh, but since the pinion 107 is now disposed on the opposite side of a plane parallel to the said pinion, and passing through the axis of rotation of the pinion 106, it will continue to rotate in 60 the same direction about its own axis, notwithstanding the reversal in direction of rotation of the cranking shaft 99.

While the embodiment of the invention herein 65 illustrated, and above described in detail, is regarded as of considerable practical merit, it is to be understood that variations may be made in the arrangement of the gears and the other elements of the assembly, and such variations as are not expressly prohibited by the language of the broad- 70 est of the appended claims are to be considered as embraced therein.

What is claimed is:

1. In an engine starter of the type wherein an engine engaging member, a driving member, and 75 motion transmitting connections therebetween,

are enclosed in a sectional casing through one end of which the engine engaging member extends, the combination with said driving member and engine engaging member, means for energizing said driving member including a laterally 5 displaceable shaft disposed transversely with respect to the axis of rotation of said engine-engaging member, means including interchangeable clutch teeth mounted on a common longitudinally disposed shaft, said shaft being shiftable 10 end for end for drivably connecting said transversely disposed shaft with said driving member, a pair of casing sections having parallel bearing surfaces to support said laterally displaceable shaft, and common means extending through both said parallel surfaces to retain said laterally displaceable shaft in any selected one of a plurality of positions.

2. In an engine starter of the type wherein an engine engaging member, a driving member, and motion transmitting connections therebetween, 20 are enclosed in a sectional casing through one end of which the engine engaging member extends, the combination with said driving member and engine engaging member, means for energizing said driving member including a laterally 25 displaceable shaft disposed transversely with respect to the axis of rotation of said engine-engaging member, a driving gear and a driven gear shiftable to mesh with said driving gear at diametrically opposite positions in the plane of said laterally displaceable shaft, a pair of casing sections having parallel bearing surfaces to support said laterally displaceable shaft, and common 30 means extending through both said parallel surfaces to retain said shaft in any selected one of a plurality of positions.

3. In an engine starting mechanism comprising a driving member, an engine engaging member, and a gear train drivably connecting said 40 members, the combination with said gear train and members of a sectional casing enclosing and supporting said gear train, said casing including two laterally extending spaced apart portions, a shaft 45 extending through the space thus provided into operative engagement with said gear train, and supporting means surrounding said shaft, said supporting means being in the form of a substantially cylindrical member, the outer cylindrical surface of which is slidable along surfaces 50 of said laterally extending portions in response to angular adjustment of said shaft about a point on the longitudinal axis thereof.

4. In engine starting mechanism comprising a driving member, an engine engaging member, and a gear train drivably connecting said members, the combination with said gear train and members of a sectional casing enclosing and supporting said gear train, said casing including two laterally extending spaced apart portions, a shaft 60 extending through the space thus provided into operative engagement with said gear train, and supporting means surrounding said shaft, said supporting means being in the form of a substantially cylindrical member, the outer cylindrical surface of which is slidable along surfaces 65 of said laterally extending portions in response to angular adjustment of said shaft about the axis of rotation of a member of said gear train.

5. In engine starting mechanism comprising a driving member, an engine engaging member, and a gear train drivably connecting said members, the combination with said gear train and members of a sectional casing enclosing and supporting said gear train, said casing including 70

two laterally extending spaced apart portions, a shaft extending through the space thus provided into operative engagement with said gear train, and supporting means surrounding said shaft 5 and supported at either side on said laterally extending portions, said supporting means being in the form of a substantially cylindrical member the outer cylindrical surface of which is slidable along surfaces of said laterally extending portions in response to angular adjustment of said shaft about the longitudinal axis of said cylindrical member.

6. In an engine starter of the type wherein an engine engaging member, a driving member, and 15 motion transmitting connections therebetween, are enclosed in a sectional casing through one end of which the engine engaging member extends, the combination with said driving member and

engine engaging member, means for energizing said driving member including a laterally displaceable shaft disposed transversely with respect to the axis of rotation of said engine-engaging member, means comprising a member having annular internally toothed portions, a gear on said transversely disposed shaft, an intermediate member having teeth adapted to mesh with both said gear and said internally toothed annular member, and a second set of teeth adapted to mesh with said internally toothed member only upon end to end reversal of said intermediate member, a pair of casing sections having parallel bearing surfaces to support said laterally displaceable shaft, and means common to both said 15 parallel surfaces to retain said shaft in any selected one of a plurality of positions.

RAYMOND P. LANSING.
